AMALGAMATOR.

1,005,105.

Specification of Letters Patent.

Patented Oct. 3, 1911.

Application filed April 26, 1911. Serial No. 623,355.

To all whom it may concern:

Be it known that I, CHARLES F. DAVIS, citizen of the United States, residing at Tallapoosa, in the county of Haralson and 5 State of Georgia, have invented certain new and useful Improvements in Amalgamators, of which the following is a specification.

My invention relates to improvements in amalgamators having for its object to provide a machine which is simple and cheap 10 in construction, which may be readily assembled and taken apart, and which is adapted for use in connection with any type of gold mine milling machinery, receiving 15 the material to be treated either directly from the stamp mill or other machinery for pulverizing same, or it may be used at the head or discharge end of a concentrator and consists essentially in the provision of an 20 oscillatory casing subdivided by transverse horizontal amalgamated plates which are slotted to cause the material to flow in a tortuous passage from bottom to top, the material to be treated being fed to the amalgamator 25 from an elevation sufficient to insure the gravity feed upward through the amalgamator.

One important feature of my invention consists in adapting the material to flow 30 upwardly between the amalgamated plates in the amalgamator, this arrangement reducing the loss of mercury to a minimum and adapting the amalgamator to catch the mercury with its contents of gold which is 35 lost by globularization from the plates of the stamp mill.

Another feature of my invention is the provision of a receptacle at the bottom of the amalgamator in which I provide a pool 40 of mercury with which the material first comes in contact before it starts its back and forth upward travel across the amalgamated plates. I have found that the oscillation or shaking of the amalgamator is important 45 for preventing the heavy material from settling on the amalgamator plates and banking them up with concentrates and like heavy material, thereby keeping the plates clean for proper action on the gold in the 50 material under treatment. The advantage of causing the material to flow upwardly through the amalgamator is to prevent loss of the mercury, for if any works off the plates, instead of escaping with the material 55 and losing its gold, it will work back down

to the pool of mercury in the basin at the bottom of the casing and be preserved.

My apparatus is very effective to catch the mercury and its gold contents lost by globularization from the stamp mill plates. 60

My invention further comprises the details of construction and arrangement of parts hereinafter described and claimed, reference being had to the accompanying drawings, in which:—

Figure 1 is a vertical sectional elevation through the amalgamator. Fig. 2 is a side elevation on a smaller scale showing the mechanism for feeding and oscillating the amalgamator. Fig. 3 is a detail perspective view of several of the amalgamated plates shown detached with arrows illustrating the direction of flow of the material under treatment.

Similar reference numerals refer to similar parts throughout the drawings.

The material to be treated, after being reduced to the proper condition for the extraction of the gold therefrom in the amalgamator, is introduced into a tank or hopper 80 1 from which it flows down by gravity through a flexible section of hose pipe 2 which is connected by couplings 3 and 4, respectively, with the tank 1 and with an elbow or quarter bend 5 which is bolted or otherwise secured to the inlet pipe 6 which leads to the bottom of the amalgamator casing 7. The passage 8, in the pipe 6, is round at its intake end and is gradually spread out toward its discharge end 9 which delivers 90 the material in a thin sheet onto the bottom 10 of the amalgamator casing. This bottom is depressed at its center to form a basin in which a body of mercury 11 is introduced and which is provided with a bottom drain 95 opening normally closed by a screw plug 12.

The sides of the amalgamator casing at the bottom are formed with an off set shoulder 13 upon which rests a horizontal amalgamated plate 14 provided across its end 100 farthest from the inlet port 9 with a narrow transverse slot 15 which extends the greater portion of the width of the plate. A half inch strip of hydraulic packing 16 is disposed around the marginal edges of the 105 plate 14 and is adapted to support in spaced relation therefrom a second plate 14 which has its slot 15 at the opposite end from the slot in the plates above and below it. As will be seen in Fig. 1, the entire body of the 110

amalgamator casing 7 has these plates 14 nested therein with their ports 15 staggered so that the material will flow back and forth from end to end with the casing in 5 passing from the bottom inlet to the outlet port 17 formed in the top plate 18, which is suitably bolted to the casing 7. The plates 14 are silvered on both sides and the material passes between them in shallow 10 sheets which effectively brings all of the gold therein into contact with the amalgamated surface of one of the plates before it has traveled the long distance provided for in passing through the machine. The 15 lugs 19 are cast integral with the end of the casing and disposed at each side thereof and a pitman 20 is pivotally connected to each, each shaft being oscillated by an eccentric 21 on a shaft driven by the pulley 20 22 and mounted in bearing standards 23.

To provide for oscillating the amalgamator I attach to its bottom, near each end, covered blocks 24, which receive the upper ends of rocking supports 25, which at their 25 bottoms rest in bearing blocks 26 similar to 24 and mounted in a base plate 27, which base plate is also extended sufficiently to have the standards 23 bolted thereto.

In operation, the material to be treated 30 flows by gravity through the pipes 2 and 5 and through the inlet port 9, entering the bottom of the amalgamator casing where it first comes into contact with the pool of mercury 11. The head pressure is sufficient 35 to force the material in its tortuous upward passage back and forth across the plates 14 until it passes out through the top discharge port 17, all the fine floured gold and the floured amalgam being given ample 40 opportunity in the long travel of the material to amalgamate on the plates. The eccentric mechanism described gives a continuous oscillation of the amalgamator thereby preventing the heavy material settling 45 on the plate and facilitating the gravity flow of the material from bottom to top through the casing. By arranging the plates horizontally I minimize their tendency to lose their amalgam surfacing which 50 would tend to form into globules and run off an inclined plate much more readily than from a horizontal plate. Also this increases the distance of travel I can give the material in a casing of a given size. The 55 upflow of the material over the pool of mercury will have a tendency to keep the plates amalgamated or requickened and thereby increase the effectiveness of the machine.

The top cover can be readily removed and the plates 14 lifted out, cleaned and replaced 60 with small expense and little delay. By screwing the cover down on the plates after they are assembled in the casing, they are pressed against the packing rings sufficiently to prevent the material passing around the 65 edges of the plates.

While I have illustrated the preferred embodiment of an apparatus for carrying my invention into practice, I am aware that many minor changes in detail may be made 70 without, however, departing from the spirit of my invention and without therefore specifically limiting myself to the details of construction shown.

Having thus described my invention, 75 what I claim as new and desire to secure by Letters Patent, is:—

1. An amalgamator comprising in combination a casing, closely spaced plates disposed therein in horizontal planes and amalgamated on both sides, there being passages provided at alternately opposite ends of the plates for the material to be treated, the casing being provided with a feed inlet at the bottom and an outlet at the top, and 80 means for shaking the casing and its contained plates, substantially as described.

2. In an amalgamator comprising in combination a casing, closely spaced plates disposed therein in horizontal planes and amalgamated on both sides, said plates being provided with passages at alternately opposite ends, the casing being provided with a feed inlet at its bottom and an outlet at 90 the top, and means for shaking the casing 95 and its contained plates, substantially as described.

3. An amalgamator comprising in combination a casing, closely spaced plates disposed therein in horizontal planes and amalgamated on both sides, there being passages provided at alternately opposite ends of the plates for the material to be treated, the casing being provided with a feed inlet at the bottom and an outlet at the top, and the 100 bottom part of the casing being adapted to contain a mercury bath, and means for shaking the casing and its contained plates, 105 substantially as described.

In testimony whereof I affix my signature 110 in presence of two witnesses.

CHARLES F. DAVIS.
